IMPACT BREAKER BAR MECHANISM

Leo H. Long, Burton, Wash.

Application August 21, 1950, Serial No. 180,555

4 Claims. (Cl. 241—197)

1

My invention relates to impact resistance inserts for crusher bars used particularly in connection with the crushing or dividing of rock and the like.

As an illustration, but not as a limitation of my invention, the insert devices and mechanisms of my invention may be used in connection with the device illustrated in United States Letters Patent No. 2,486,421, issued Nov. 1, 1949, wherein Lee H. Kessler is the inventor.

Such prior art impact breaker devices employed radially directed rotatably mounted impact breaker blades or bars. Such blades or bars were removably mounted. In actual practice, it was found that such members must be made of a steel alloy which had characteristics which were a compromise between desired characteristics. In other words, it was necessary to provide such impact bars with sufficient tensile strength to withstand breakage and fracture at the expense of characteristics against wear and abrasion. Thus, the impact bars of the prior art were characterized with a relatively short life.

It is an object of my invention to provide impact breaker bars with inserts thereon of a character so that the breaker bars have not only desired resistance against breakage but have desired resistance against wear and abrasion.

It is a further object of my invention to provide impact insert means for breaker bars, which insert means may be properly fitted in place with a minimum of machining, are easily removed and inserted in place, have a maximum life, and are substantially free of mechanical difficulties during normal life thereof.

Other objects and advantages of my invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described, since obvious modifications will occur to a person skilled in the art.

Figure 1 is a view in side elevation, with parts broken away, showing generally a crusher where-in devices of my invention are generally indicated;

2

Fig. 2 is a fragmentary perspective view, on a larger scale than Fig. 1, of a crusher bar assembly embodying my invention;

Fig. 3 is a detached view in bottom plan illustrating an insert of my invention;

Fig. 4 is a view in section, taken substantially on broken line 4—4 of Fig. 3 and further showing the same attached to a crusher bar, only a fragment of the crusher bar is shown and the nut and bolt means have been loosened for purposes of illustration;

Fig. 5 is a sectional view taken substantially on broken line 5—5 of Fig. 3; and

Fig. 6 is a view in cross section of a stationary breaker bar embodying my invention.

Referring now to Fig. 1 of the drawings, a typical installation involving my invention employs rotors 10 and 11 driven by any suitable means (not shown) in opposite directions as indicated by the arrows. Each of the rotors 10 and 11 detachably mounts impeller crusher bars 12. This may be accomplished by any usual means, such as wedges 13, and nut and rod means 14. By tightening of the nut means relative to the rod means of nut and rod means 14, the wedges 13 are caused to move longitudinally as well as crosswise, and thus firmly secure each of the impeller bars 12 rigid relative to the rotor 10 or 11 mounting the same.

As indicated in said Fig. 1 of the drawings, pieces of rock are fed inwardly by infeed conveyors 15, and permitted to drop downwardly on rotors 10 and 11. Such pieces of rock are contacted by the impeller bars 12 and urged relatively radially upward and into contact with breaker bars 16. Due to impact, the rock is crushed or divided into smaller pieces, and then the pieces of rock fall downwardly. If the pieces of rock are small enough, they will pass downwardly on either side of the machine adjacent breaker bars 17 and to the outfeed portion of the machine 18. However, if one impact is not sufficient, the pieces of rock will be again tossed generally radially upwardly by the impeller bars 12 and against breaker bar 16 until the average size piece of rock is of the desired size, and thereupon such smaller pieces will be delivered to the outfeed portion 18 of the machine.

The general arrangements of a crusher which may employ my invention is illustrated in said patent to Lee H. Kessler and hence no further

detailed description will be given of such typical construction to which my invention is applicable.

Referring now to Fig. 2 of the drawings, a plurality of longitudinally aligned impeller bars 12 are illustrated. In said Kessler patent, and particularly in Fig. 6 thereof, a symmetrical impeller bar 22 is indicated, which was designed to be removed and rearranged from time to time to permit the wearing off of four wearing surfaces. I have found that the time and expense involved in so adjusting the impeller bars to wear off four surfaces is not practically feasible and economical. Thus, I have provided an end portion 19 on each impeller bar 12 which is used for detachably securing each impeller bar 12 to a desired rotor 10 or 11. The other end portion 20 has a depression formed by machined surfaces 22 and 23 and cast surfaces 24, 25, and 26. The surfaces 24 and 26 should have an angle of approximately 120° to the surface 25 to insure proper results in casting, and at the same time adequate strength to properly support the insert 27.

Referring now more particularly to Figs. 3 to 5 inclusive, each insert 27 may be made wholly by casting and such inserts have a relatively short length, such as between four and five inches long, and a number thereof will be placed lengthwise of the depression or groove formed by surfaces 24, 25, and 26 of each impeller bar 12. In practice, the impeller bars 12 are often made in lengths in the order of twenty and thirty inches, and hence on such impeller bars there will be four or six inserts longitudinally aligned in each depression or groove formed by surfaces 24, 25, and 26.

Each of the inserts 27 comprises shoulders or lug-like protruding portions 28, which are of a size, shape and contour to interfit with a portion of the depression or groove formed by surfaces 24, 25, and 26. A double keyhole slot is provided in each of the inserts 27 and aligned with the lug or shoulder means 28. Such double keyhole slot (see Fig. 3) provides an enlarged opening 30 and smaller end openings 31. The smaller end openings 31 are formed by shoulder portions 32 (see Fig. 4) and the head portion of bolt 33 may be inserted through the enlarged opening 30 and then moved longitudinally of the keyhole slot and under shoulders 32. Thereafter, the stock portion of said bolt 33 may be inserted through opening 34 (see Figs. 2 and 4) and suitable nut means 35 may be tightened on the threaded stock of bolt 33 to secure each insert 27 in place. The impeller bar 12 is provided with a plurality of spaced openings 34 so that two bolts 33 may be employed to secure each of the inserts 27 in place.

As the portion of an insert 27 away from the groove or depression formed by surfaces 24, 25, and 26 is subjected to wear, the heads of the bolts 33 are protected by the insert and are not subjected to wear. During operation, and if the lower portion of the insert 27, as is indicated in Fig. 5, is the leading edge, then the wear will reach substantially to the dash line 36 as appears in said figure. If the impeller bars are thereafter reversed and the upper edge of the insert 27, as is shown in Fig. 5, is the leading edge, then the wear may reach to the dot-and-dash line 37 as shown in said figure. When the insert has worn so that the outer surface thereof comprises an inner line common to lines 36 and 37, then it is desirable to replace the inserts. While it is desirable to replace all inserts at one

time, to maintain proper dynamic balance of the rotors 10 and 11, in actual practice it has been found that it is not positively essential to replace all inserts 27 at one time, and they may be replaced individually.

In practice I have found it desirable to make the impeller bars 12 out of manganese molybdenum steel, heat treated to a "Brinell" hardness of about 250 to 350. Such type of material will have the desired tensile strength to prevent breakage and the like. On the other hand, I preferably cast the inserts 27 from manganese molybdenum titanium alloy, heat treated to a hardness of about 500 to 600 "Brinell." While inserts 27 cast of such material have a normal tendency to be brittle because of their high degree of hardness, the inserts 27 of my invention, in fact, are not fragile and do not tend to readily break, due to the support which they receive by reason of machined surfaces 22 and 23 of impeller bar 12, which contact with the surfaces 38 and 39 of the inserts 27. When the inserts 27 are in place (as is indicated by Fig. 2 of the drawings) the surfaces 38 and 39 rest firmly against the machined surfaces 22 and 23, while there is clearance between the shoulders or lugs 28 of the inserts 27 and the cast surfaces 24 and 26 of the impeller bar 12. Also there is a clearance between the cast surface 25 of the impeller bar 12 and the protruding end portions of the lugs or shoulders 28 of each insert 27. Furthermore, I am able to cast the inserts 27, and no machining is required because of the relatively short length and width of the surfaces 38 and 39. This is of extreme value, due to the hardness of the metal alloy employed in casting inserts 27 and the obvious difficulty of machining such metal alloy.

Referring now to Figs. 1 and 6 of the drawings, each of the stationary breaker bars 16 is mounted to be in the line of travel of particles of rock emanating from the moving impeller bars 12. Preferably, each of the stationary bars 16 is made of a steel alloy similar to that employed in casting impeller bars 12. Also, each of the stationary breaker bars 16 is provided with a groove or trough 40 similar to the groove or trough in the impeller bars 12. A plurality of inserts 41 are longitudinally aligned and have shoulder portions 42 in the groove or trough 40 of the stationary breaker bars 16. The said breaker bars 16 are non-rotatably mounted by any common expedient, such as a squared cross-section as shown, and the same are initially adjusted so that the surface 43 of the inserts 41 are in the line of travel of pieces of rock emanating from the driven impeller bars 12.

The construction and means of mounting of the inserts 41 may be similar to that indicated in connection with the inserts 27 and hence I have also shown bolts 44 which, like bolts 33, will be protected against wear. In view of the fact that similar characteristics are desired as respects breaker bars 16 and inserts 41 to impeller bars 12 and inserts 27, the same may be made respectively of similar steel alloys. From the similarity of the construction indicated in Fig. 6 to the construction of the inserts 27 and impeller bars 12, no further description is believed necessary.

Preferably, the inserts 41 and the inserts 27 are duplicates as to size and metal alloy and thus when the inserts 27 have lost their utility as inserts for impeller bars 12 (they have worn down to the inner common surface of lines 36 and 37

in Fig. 5), they may be used as inserts in the breaker bars 16. Obviously, there is much more wear and abrasion to inserts employed on the impeller bars 12 than there is on inserts employed in connection with breaker bars 16. Thus, whenever inserts are replaced on the impeller bars 12 they can be replaced as a unit, as the inserts will have further utility and use in connection with the stationary breaker bars 16. In other words, the rotors 10 and 11 may be maintained in dynamic balance by complete replacement of inserts 27 upon wear of the same, and such inserts 27 may be utilized for their substantial complete life by using them in connection with the stationary breaker bars 16.

In the foregoing description, I have described use of inserts 41 or inserts 27 in connection with bars 16, but such is not intended as a limitation as the same inserts are illustrated for use in connection with the stationary breaker bars 17. Stationary breaker bars 17 may be duplicates of stationary breaker bars 16 but the bars are given different numbers to indicate the respective positions thereof.

From the foregoing, it will be obvious that a successful insert for a stationary or a moving breaker bar must be characterized by having detachable means which are protected against wear. Next, it will be obvious that I must provide an insert of a type and character which may be used directly after casting without further machining thereof, and in such connection the character of the engaging means requires a particular type of stationary or moving crusher bar as well as a particular type of insert.

During operation of devices embodying my invention, the inserts 27 will tend to move outwardly and the thrust will be against the surface 24 and the surface 22 of the impeller bar 12. Thus, the bolt 33 does not carry any substantial portion of the strain and no difficulties have been encountered with bolt breakage. This, of course, is important for if an insert should become loosened and tossed by the rotors 10 and 11, substantial damage might occur due to the extreme hardness of the inserts. Similarly, the inserts 41 employed in connection with stationary breaker bars 16 and 17 will have the load carried in a similar manner and thus bolts 44 do not carry any load which in any wise tasks their strength.

From the foregoing description of my invention it will be apparent that I have provided an impact breaker bar comprising a base member such as fixed breaker bars 16 and 17 or revolvably mounted impeller bars 12. Each of these said base members provides a wedge-shaped longitudinally extending groove formed by machined surfaces 22 and 23, which lie in a common plane, inwardly inclined surfaces 24-26, and a bottom surface 25. Next, I have provided a detachable breaker impact member, as inserts 27 or inserts 41. The inserts have mating surfaces to the surfaces or faces of the trough in the base member. Thus, surfaces 22 and 23 fit snugly against the surfaces 38 and 39, and it is not necessary to machine the surfaces 38 and 39 of the detachable breaker impact members 27 or 41. The faces 24, 25, and 26 loosely mate the paired surfaces of the insert 27 provided by the lugs or shoulders 28. Next, the detachable breaker impact members 27 or 41 are held in place by bolts which have their head portions held in place by the shoulders 32 which form the keyhole slot 30-31. The bolts 44 extend through suitable apertures in the base members 16, 17 and 12, and nuts are

provided away from the line of travel of pieces of rock to be crushed or divided.

Obviously, changes may be made in the form, dimensions and arrangement of the parts of my invention, without departing from the principle thereof, the above setting forth only a preferred form of embodiment.

I claim:

1. An impact mechanism comprising a driven rotor; detachable impeller bars; means securing said impeller bars to said rotor, said impeller bars projecting radially outwardly from the periphery of said rotor, each of said impeller bars being formed of ferrous manganese alloy and having a "Brinell" hardness of about 250 to 350, and having a wedge-shaped groove therein, the wall of said groove extending angularly and converging inwardly and with machined shoulders adjacent the groove, said groove extending parallel to the axis of the rotor, each of said impeller bars having an aperture extending from the bottom of said groove through the impeller bar; a detachable breaker impact member secured to each of said impeller bars and each being formed of ferrous manganese alloy and heat treated to a "Brinell" hardness of about 500 to 600, having an impact face on one side thereof, having on the opposite side thereof a projecting boss longitudinally extending throughout the length thereof and loosely mating crosswise one of said grooves in said impeller bar, and having shoulders adjacent said boss snugly fitting the machined shoulders of one of said impeller bars; bolt head supporting means carried by each of said detachable breaker impact members and disposed away from said impact face; and bolt and nut means having the bolt-head thereof secured to said bolt supporting means, projecting through said aperture in said impeller bar, and held in place by the nut thereof.

2. An impact mechanism comprising a driven rotor; detachable impeller bars; means securing said impeller bars to said rotor, said impeller bars projecting radially outwardly from the periphery of said rotor, each of said impeller bars having a wedge-shaped groove therein, the walls of said groove extending angularly and converging inwardly and with machined shoulders adjacent the groove, said groove extending parallel to the axis of the rotor; a detachable breaker impact member secured to each of said impeller bars and each formed of ferrous manganese alloy and heat treated to a "Brinell" hardness of about 500 to 600, having an impact face on one side thereof, having on the opposite side thereof a projecting boss longitudinally extending throughout the length thereof and mating crosswise of said grooves in said impeller bar, and having shoulders adjacent said boss interfitting the machined shoulders of one of said impeller bars; and detachable securing means securing said detachable breaker impact members to said detachable impeller bars.

3. The combination of claim 2, wherein a plurality of detachable breaker members are secured in the groove of each impeller bar.

4. An impact mechanism comprising a driven rotor; detachable impeller bars; means securing said impeller bars to said rotor, said impeller bars projecting radially outwardly from the periphery of said rotor, each of said impeller bars being formed of ferrous manganese alloy and having a "Brinell" hardness of about 250 to 350, and having a wedge-shaped groove therein, the walls of said groove extending angularly and converging

ing inwardly and with machined shoulders adjacent the groove, said groove extending parallel to the axis of the rotor, each of said impeller bars having an aperture extending from the bottom of said groove through the impeller bars; a detachable breaker impact member secured to each of said impeller bars and each being formed of ferrous manganese alloy and heat treated to a "Brinell" hardness of about 500 to 600, having an impact face on one side thereof, having on the opposite side thereof a projecting boss longitudinally extending throughout the length thereof and loosely mating crosswise one of said grooves in said impeller bar, having shoulders adjacent said boss snugly fitting the machined shoulders of one of said impeller bars; detachable securing means securing each of said impact breaker members to a said impeller bar comprising spaced shoulders having a groove therebetween and a keyhole slot forming member associated therewith; and a plurality of bolt and nut means having the bolt-head portion of each thereof detachably secured to said keyhole slot forming member, projecting through the aperture in said impeller bar, and held in place by the nut thereof.

LEO H. LONG.
